UNITED STATES PATENT OFFICE.

GEORG SCHENK, OF NUERMBERG, GERMANY, ASSIGNOR TO THE FIRM OF MÖBEL-FABRIK UND VERTRIEBSGESELLSCHAFT M. B. H., OF NUERMBERG, BAVARIA, GERMANY.

METHOD OF PRODUCING OAK IMITATION BY DEEP PORING UPON COMMON WOOD AND UPON METAL SURFACES.

1,408,643.

Specification of Letters Patent.

Patented Mar. 7, 1922.

No Drawing.

Application filed August 5, 1921. Serial No. 490,128.

To all whom it may concern:

Be it known that I, GEORG SCHENK, a citizen of the German Republic, residing at Nuremberg, Germany, have invented certain new and useful Improvements in Methods for Producing Oak Imitation by Deep Poring Upon Common Wood and Upon Metal Surfaces, of which the following is a specification.

10 This invention has for its object a method for producing oak imitation by deep poring upon common wood and metal surfaces. This method can be used for giving to pieces of furniture made from common wood the 15 appearance of oak furniture. It can further be used for giving the appearance of oak wood to metal surfaces. In both cases a soft ground is produced upon the surfaces by means of an oil containing mass, whereupon 20 by means of convenient devices oak veinings are deeply impressed in this soft ground so that the veinings will be everlasting.

The invention makes it possible to use for 25 furniture and other purposes common wood so that the cost of manufacture is considerably reduced.

The method consists in coating the surface of the wood or the surface of a metal piece with a layer of a material which contains oil 30 and which is adapted to be brought on with

a spatula, this layer being of any convenient thickness; whereupon the coating is painted with oil colour and varnished. In the surface thus prepared the oak veining is impressed deeply by means of rollers or other devices of convenient construction which carry the pattern in relief, whereupon the surface is stained and matted.

Owing to this improved method wood can be used which is full of knots, as the knots are covered by the thick coating.

I claim:—

A method for the production of oak imitation upon common wood or metal surfaces by deep poring, consisting in covering the entire surface with a layer of an oil containing mass adapted to be brought on with a spatula, in painting this coating with oil colour and in varnishing the same, in treating the thus prepared surface with convenient instruments for producing deep pores imitating oak veining, in staining and in matting the surface.

In testimony whereof I affix my signature in presence of two witnesses.

GEORG SCHENK.
